DESIGN FOR A BOTTLE CAP

George Switzer, New York, N. Y., assignor to
Lyons-Magnus, Incorporated, doing business as
The E. G. Lyons & Raas Company, San Fran-
cisco, Calif., a corporation of California

Application March 7, 1935, Serial No. 55,778

Term of patent 14 years

To all whom it may concern:

Be it known that I, George Switzer, a citizen of the United States, residing at 25 Central Park West, New York city, in the county of New York and State of New York, have invented a new, original, and ornamental Design for a Bottle Cap, of which the following is a specification, reference being had to the accompanying drawing forming a part thereof.

Figure 1 is a top plan view of a bottle cap embodying my new design.

Figure 2 is a front elevational view of the bottle cap shown in Figure 1.

Figure 3 is an end view of the bottle cap shown in Figure 1.

The dominant features of the design are the plane edges of the cap and the grooves extending across the rounded top at each side and bordering the outline of the ornamental figure between each groove and the edge of the cap.

I claim:

The ornamental design for a bottle cap substantially as shown and described.

GEORGE SWITZER.
